United States Patent Office

Des. 182,718
Patented May 6, 1958

182,718

TOOL HOLDER

Raymond T. Gutz, Aurora, Ohio, assignor to True Temper Corporation, Cleveland, Ohio, a corporation of Ohio

Application March 8, 1957, Serial No. 45,168

Term of patent 14 years

(Cl. D80—10)

Fig. 2

Fig. 1 is a rear perspective view of a tool holder showing my new design; and Fig. 2 is a front perspective view thereof. The tools shown in the figures in broken lines are for purposes of illustration only.

I claim:

The ornamental design for a tool holder, as shown and described.
